CLAIM

The ornamental design for an air conditioning apparatus, as shown and described.

DESCRIPTION

FIG. 1 is a right bottom front perspective view, showing the air conditioning apparatus of my new design, the air hose omitted for clarity of illustration;

FIG. 2 is a right top front perspective view thereof;

FIG. 3 is an enlarged bottom plan view thereof;

FIG. 4 is a top view thereof with an air hose installed;

FIG. 5 is a bottom view thereof similar to FIG. 3;

FIG. 6 is a right side view of the air conditioning apparatus shown in FIGS. 4 and 5;

FIG. 7 is a left side view thereof; and,

FIG. 8 is a front perspective view thereof.
